TRANSCRIBING UNIT FOR A DICTATION SYSTEM

Fred C. Bolick, Jr., Atlanta, Ga., assignor to Lanier Electronic Laboratory, Inc., Atlanta, Ga., a corporation of Georgia

Filed Apr. 16, 1969, Ser. No. 16,760

Term of patent 14 years

Int. Cl. D14—01

U.S. Cl. D26—14

FIG. 1

FIG. 3

FIG. 2

FIG. 5

FIG. 4

FIG. 1 is a perspective view of a transcribing unit for a dictation system showing the design;

FIG. 2 is a top plan view of the transcribing unit for a dictation system shown in FIG. 1;

FIG. 3 is a side elevational view of the transcribing unit for a dictation system shown in FIG. 1;

FIG. 4 is a rear elevational view of the transcribing unit for a dictation system shown in FIG. 1;

FIG. 5 is a bottom plan view of the transcribing unit for a dictation system shown in FIG. 1.

I claim:

The ornamental design for a transcribing unit for a dictation system, substantially as shown.
